UNITED STATES PATENT OFFICE.

JOHN ELNIEFF, OF KANSAS CITY, MISSOURI.

WINDOW CONSTRUCTION.

1,414,776.

Specification of Letters Patent. Patented May 2, 1922.

Application filed July 25, 1921. Serial No. 487,220.

To all whom it may concern:

Be it known that I, JOHN ELNIEFF, a citizen of the United States, residing at Kansas City, in the county of Jackson and State of Missouri, have invented a certain new and useful Improvement in Window Construction, of which the following is a complete specification.

This invention relates to window construction and has for its objects to produce a window at less cost of manufacture and installation than the conventional type, which is more hygienic in that it makes provision for more efficient circulation of air by insuring the escape of the strata adjacent the ceiling, which more perfectly excludes dust, air and rain and cannot rattle, which may be washed without necessitating the cleaner to assume a dangerous position, and in which the glass can be replaced without removal of the sash by a person standing in the room. A further object is to produce a window construction embodying the features of simplicity, strength and durability in a high degree.

With these objects in view, the invention consists in certain novel and useful features of construction and combinations of parts as will hereinafter appear; and in order that it may be fully understood, reference is to be had to the accompanying drawing, in which:

Figure 1 is a fragmentary elevation of the window from the outer side of the same.

Figure 2 is a central vertical section taken on the dotted line II—II of Figure 1.

Figure 3 is a fragmentary elevation of the inside of the window.

Figure 4 is a horizontal section of the window taken on the dotted line IV—IV of Figure 3.

Figure 5 is a horizontal section taken on the line V—V of Figure 3.

Figure 6 is a fragmentary vertical section taken through the transom bar of the window.

Figure 7 is a similar view taken through the bottom part of the window frame.

In the said drawing which discloses a window frame designed primarily for use in a brick building, and which may be modified without invention for use in a frame or other building, 1 indicates the sides or jambs of the window frame, 2 the sill thereof, 3 the stool, and 4 the top of the frame.

At its inner side the frame is provided with a top casing 5 and side casings 6 extending

from the stool to casing 5, and at the outer side of the frame, there are provided the brick moulding 7 extending vertically and the top moulding 8. Secured to the outer faces of the sides of the frame are brick anchors 9.

Extending from one jamb to the other is a transom bar 10, and mounted thereon and sloping downward and outward slightly is the transom sill 11. Secured to the lower face of the top 4 is a split top stop 12, the inner section of which is provided at its lower margin with an inwardly-projecting tongue 13.

The sides 1 are formed with inwardly-facing vertical shoulders 14, and secured to the inner faces of the sides and extending from the stool 3 to the transom bar 10 are vertical side stops 15 provided at their inner margins with vertical tongues 16. Similar side stops 15^a aligned with stops 15, extend from the transom bar sill 11 to the top stop 12 and said side stops 15^a are provided with inwardly-projecting tongues 16^a.

A top stop for the window opening between the stool 3 and the transom bar 10, is secured to the under side of the latter and is identified by the reference character 17, and is provided at its lower inner margin with an inwardly-projecting tongue 18. The inner edges of the various stops mentioned stand in the same vertical plane and the same statement applies to the inner edges of the respective tongues of said stops.

A screen 19 preferably of copper wire, is secured at its upper end in the slit 20 of the top stop 12. At its lower end it is flanged or bent outward as at 21, and secured to the transom bar sill 11, the side edges of said screen being secured in splits provided in the side stop 15^a.

From the foregoing it will be seen that the openings both above and below the transom bar 10, are provided with top stops 100 having inwardly projecting tongues and side stops having similar but vertical tongues. Both openings are provided also with bottom tongues, that is to say, the transom bar sill 11 is provided with an upwardly-projecting tongue 22 and the sill 2 with a similar tongue 23, the outer sides of said tongues sloping upwardly and inwardly for a purpose which is hereinafter explained. The form of said tongue can be seen more clearly by reference to Figures 6 and 7.

A transom is provided as a closure for

the opening above the transom bar, and is adapted to fit snugly in said opening and against the side stop 15^a and the split top stop 12, and said transom is hinged as at 5 25 to the transom bar sill 11. To establish a perfectly tight joint for the exclusion of air and water from the room, grooves are provided in the outer face of the transom for the reception of the respective tongues. 10 By reference to Figure 2, it will be seen that the top rail of the transom is provided with a groove 26 receiving the tongue 13 of the top stop, and by reference to Figure 5, it will be noted that the side rails of the transom are provided with vertical grooves 27 (one only appearing) for the reception of the tongues 16^a of the side stops 15^a. The bottom rail of the transom is provided in its lower edge with a groove 28 conforming 20 to and receiving the tongue 22, that is to say, the outer wall of the groove and the outer sloping face of the engaging tongue extend substantially concentrically of the hinged point of the transom bar, as otherwise a snug and accurate fit between the tongue 22 and groove 28 could not be made. 25

The transom is provided with a conventional latch 24^a for fastening it in its closed position. To support it in an opened position, as indicated by dotted lines in Figure 30 2, a chain 29 is secured to a staple 30 secured in one of the side stops 15^a, and is adapted to engage a hook 31 secured to the transom. When the transom is closed the chain hangs 35 in substantially the position indicated between the screen and the transom. When the latter is opened the chain extends obliquely from the staple 30 to the hook 31, as indicated by dotted lines in Figure 2. By 40 engaging different links of the chain with the hook, the transom may be supported in partly opened position.

To close the lower or large opening of the window a sash 32 is provided, and the 45 same is hinged at its lower inner margin at 33 to the stool 3, and is adapted to close against the side stops 15 and the top stop 17. The sash is also provided at its outer side with grooves for the reception of the tongues 50 of said side and top stops, said grooves being respectively identified by the characters 34 and 35. The bottom rail of the sash 32 is also provided with a groove 36 conforming in cross-section to and receiving the tongue 23 in the same manner that the 55 groove 28 of the transom receives the tongue 22 of the transom sill. It will thus be seen that the transom and the sash are provided at all four margins with a tongue and 60 groove connection with rigid parts of the window frame and hence are endowed with strength and rigidity as well as with the property of efficiently excluding air and water.

65 The sash 32 under normal conditions, re-

mains in closed position and to so secure it, suitable fastenings may be employed, those shown consisting of a pair of sash locks comprising keepers 37 secured to the jambs, and latches 38 secured to the sash. 70

The sash is adapted to open inwardly and for supporting it in the partially opened position indicated by dotted lines in Figure 2, or in a more widely opened position, it is connected by a chain 39 to a side stop 15 near the upper end thereof. One end of the chain is fastened permanently as by a staple or otherwise to said stop, and at its opposite end, it is adapted to engage a hook 40 secured to the sash. When the sash is closed the chain hangs at the outer side thereof as indicated in Figures 1 and 2, and when open or partly opened extends inwardly through the window opening, as also indicated by Figure 2. 75 80 85

From the foregoing it will be apparent that I have produced a window construction embodying the features set forth as desirable in the statement of the objects of the invention. A window construction of the type described provides for a large lower sash and therefore gives greater visibility than the conventional sash as there is no check rail or other obstruction for intercepting the vision, and such sash cannot be readily unlocked from the outside as the sash lock or sash locks are not accessible without first cutting or breaking the glass. No weights or pockets for weights, no pulleys or cords, and no parting stops, inside 90 window stops, and screen frames are necessary, and the various parts of the casing can be fitted in the shop with the great advantage thereby entailed, and as hereinbefore suggested, the window can be washed 95 with the greatest advantage and safety to the operator and the glass can be replaced without the necessity of the operator assuming a hazardous position. 100 105 110

I claim:

1. In a window construction, a frame having top and side stops provided respectively with horizontal and vertical inwardly-projecting tongues occupying the same vertical plane, and a sill having a horizontal upwardly-projecting tongue, the tongue of the sill having flat faces and the outer face sloping upwardly and inwardly, in combination with a sash fitting snugly within the frame and against the inner edges of the top and side stops, and provided with horizontal and vertical grooves receiving the horizontal and vertical tongues, respectively, the said sash having a horizontal hinge connection with the said sill approximately concentric with respect to the sloping face of the tongue of the sill, and at an intermediate point of its lower edge, having a groove conforming in cross section to and snugly receiving the last-named tongue and contacting therewith in 115 120 125 130

a plurality of planes disposed angularly with respect to each other.

2. In a window construction, a frame having a transom bar, a sill thereon provided with an upwardly-projecting tongue sloping inwardly and upwardly at its outer side, split side stops having inwardly projecting vertical tongues, a top stop split outward of the plane of said sill tongue and provided 10 with an inwardly projecting tongue, a screen secured at its upper and side margins in the splits of said top stop and said side stops

and at its lower margin to said sill, a transom upon and hinged to the inner edge of the sill and provided with a bottom groove 15 to receive the sill tongue, vertical side grooves in its outer face to receive the tongues of the side stops, and a horizontal groove in its outer face to receive the tongue of the top stop. 20

In witness whereof I hereunto affix my signature.

JOHN E. ELNIEFF.
